UNITED STATES PATENT OFFICE.

EDGAR W. FORDYCE, OF ANNISTON, ALABAMA, ASSIGNEE OF ONE-HALF TO JOSEPH SAKS, OF ANNISTON, ALABAMA.

FLUSHING APPARATUS.

1,108,496.

Specification of Letters Patent. Patented Aug. 25, 1914.

Application filed May 11, 1912. Serial No. 392,599.

To all whom it may concern:

Be it known that I, EDGAR W. FORDYCE, a citizen of the United States, residing at Anniston, in the county of Calhoun and State of Alabama, have invented certain new and useful Improvements in Flushing Apparatus, of which the following is a specification.

My invention relates to improvements in flushing apparatus, and has for its principal object the provision of simple, reliable and sanitary means for flushing lavatories, closets, urinals and other fixtures to remove therefrom any accumulation.

Another object of my invention is the provision of a flushing apparatus which may be applied to any lavatory fixture now in use without necessitating material changes in its construction, and which apparatus will effectively prevent the escape of obnoxious odors and infectious germs from the drain pipe, and its fixtures, into the room.

Another object of my invention is the provision of a flushing apparatus which may be applied to any lavatory fixture construction in a manner that will prevent a continued connection of pipes wherein a continuance of moisture from the drain pipe to the service pipe or water supply pipe will allow infectious germs to enter water standing in water supply pipes which contaminate the water and cause disease.

A further object of my invention is the provision of flushing apparatus in which the service pipe will be separated or spaced from the fixture to provide an air space through which the water may be forced under pressure and which will contain means for holding a disinfectant, when necessary, at any part thereof to insure a sanitary and desirable fixture.

I do not limit myself to the precise details of construction herein shown, but reserve the right to make such changes, alterations and modifications as fall within the scope and spirit of the invention, pertaining to each individual instalment where the use of either separated pipes, separated pipes and receiver, or a disinfectant is required between the water supply and the receptacle that carries the water to the drain.

Figure 1 is a side elevation of a lavatory fixture equipped with my improvements, a goose neck receiver being employed to form a spaced connection between the fixture and,

"a delivering pipe from a reservoir, or, a supply pipe direct from water pressure connections as the nature of the construction may require," to provide an air space between the water supply pipe and the goose neck receptacle, through which air space the water must pass before entering the goose neck receptacle that carries it to the fixture and causes a flushing of same, these features alone being the base of this application for Letters Patent,—all other features herein shown to be covered by separate and additional Letters Patent protecting their peculiar features,—they are here shown only to give the Patent Office a full and concise explanation as to how this invention will be used in conjunction with my devices and an idea as to how this invention will be used in connection with devices already constructed. Fig. 2 is a vertical section of one form of water supply valve construction. Fig. 3 is a horizontal section, on line 3-3 of Fig. 2. Fig. 4 is a side elevation, partly in section, of the complete apparatus, the trap being shirred upon its connection with the fixture, and a flexible tube being attached to the delivery pipe of the water pressure supply, to deliver a column of water under pressure against an accumulation of matter collected in the fixture, drain pipe or sewer pipe, and Fig. 5 is an enlarged detailed view in section, of the plug or stopper at the lower end of the flexible connection.

In the drawings:—The numeral 1 designates the floor, 2 a wall or support rising therefrom, 3 a box or reservoir secured to the wall, 4 a water supply pipe entering into the reservoir through an opening 5 in the floor, and 6 a lavatory fixture having a drain or discharge pipe 7 passing through an opening 8 in the floor.

The lavatory fixture has a water-tight connection 9 rotatably connected with one end of the goose neck portion of the pipe 10, the other end of which is flared to form a receiver 11. Positioned above and in alignment with the receiver and separated therefrom to form an air space is a nut 12, threaded internally upon the threaded end 13 of the water delivery pipe 14, the other end of which is threaded at 15 to engage the threads of the connection 16, a washer 17 being placed at the discharge end of the pipe 14 to contain a disinfectant.

The numeral 18 designates a valve stem 11.

having a valve seat 19 at one end in which is seated a valve 20 adapted to normally fit tightly against the inner end of pipe 14 and prevent the flow of water therethrough. The other end of the valve stem passes through a water-tight stuffing box 21 in the side of the reservoir.

The valve stem 18 is formed with a rack for a portion of its length at 22 to engage the pinion 23 on the shaft 24, rotatably journaled in a water-tight manner in the sides of the reservoir. The outer end of the shaft 24 has an arm 24' connected by a rod 25 passing through an opening 26 in the floor and pivoted at 27 to a rod 28, fulcrumed in brackets 29 depending from the floor, and pivoted at 30 to the headed push rod 31, passing through an opening 32 in the floor and adapted to receive pressure from the foot. From this construction, it will be seen that a pressure of the foot upon the push rod will cause the shaft 24 to rotate, thus rotating the pinion 23 and through its engagement with the rack of the valve stem cause the valve stem to be moved longitudinally to withdraw the valve from its engagement with the pipe 14 and permit passage of water therethrough, a guiding rod 33 being provided for the valve stem.

When the drain pipe of the bowl has become clogged, the part 10 may be turned out of the way and a flexible tube or hose 34 may be connected to the delivery pipe. This tube directs the volume of water in a restricted column to an open plug or stopper, formed with a flanged nipple 35, over

which the lower end of the hose is fitted, the lower end of the nipple being enlarged at 36 and threaded to engage the portion 37, which fits in the discharge opening 38 of the lavatory fixture. The portion 37 is formed with a flange 39, between which and the walls of the opening is confined a washer or packing 40.

From the above description, taken in connection with the accompanying drawings, the construction and operation of my improvements will be readily understood and its many advantages fully appreciated and further elaboration is deemed unnecessary, and it will therefore be apparent that I have provided extremely simple, desirable, and efficient means for accomplishing the objects heretofore stated.

I claim:-

In a flushing apparatus, the combination with the reservoir, the discharge pipe having its inner end projecting into the reservoir, the valve rod having one end guided in the reservoir and having its other end formed with a cup-shaped valve for opening and closing the said inner end of the discharge pipe, a rack formed on said valve rod, a shaft carrying a gear wheel meshing with said rack, and means for rocking said shaft to reciprocate said valve rod.

In testimony whereof I affix my signature in presence of two witnesses.

E. W. FORDYCE.
